W. H. REID

CLOSURE FOR CONTAINERS

Filed Sept. 15, 1922

Fig. 9.

Inventor

William H. Reid.

UNITED STATES PATENT OFFICE.

WILLIAM H. REID, OF BROOKLYN, NEW YORK, ASSIGNOR TO CHARLES HAMMER, OF HOLLIS COURT BOULEVARD, NEW YORK.

CLOSURE FOR CONTAINERS.

Application filed September 15, 1922. Serial No. 588,446.

To all whom it may concern:

Be it known that I, WILLIAM H. REID, a citizen of the United States, and a resident of Brooklyn, in the county of Kings 5 and State of New York, have invented certain new and useful Improvements in Closures for Containers, of which the following is a specification.

This invention relates to closures for containers, especially bottles and jars provided with lugs or screw threads on the top, whereby the closure can be screwed down on to the container, and form a tight seal, and can be readily removed by unscrewing 15 the closure.

The object of the present invention is to provide an improved closure comprising a top and a flange or skirt composed of two walls in close engagement or contact, made 20 by bending the skirt back upwardly on itself and forming locking projections in the form of lugs or threads in the skirt by inpressing both of the engaging walls and in which the raw or free edge of the upwardly bent portion 25 is covered or protected.

A further object of the invention is the provision of a catsup cap that is a cap in which the skirt or flange usually has a length substantially equal to the diameter of 30 the cap and which flange is upwardly bent and in substantial contact with itself to form a double wall provided with suitable holding means.

A further object of the invention is the provision of an improved cap in which the flange is provided with an upwardly bent portion lapping and in close engagement with the flange thereby forming a double thickness of wall in which a locking projection in the form of a continuous thread 40 is located.

In the accompanying drawing showing embodiments of my invention, Figure 1 is a vertical section through the cap provided 45 with lugs.

Fig. 2 shows a screw thread cap.

Figs. 3 and 4 show a cap with multiple threads.

Figs. 5 and 6 show caps of different shape.

50 Figs. 7, 8 and 9 show other forms of cap.

Figs. 10, 11 and 12 show one process of making the caps.

As shown in the drawing, the cap com-

prises a top 2, and a skirt or flange that projects downwardly. The skirt as shown 55 is composed of a downwardly extended portion 4 that is bent to extend upward, as at 5, in engagement with the portion 4. Thereby is formed a double walled skirt. This double wall is pressed at intervals to form inwardly projecting lugs 6, Fig. 1. These lugs it will be seen have double walls in engagement, and therefore can strongly resist pressure when they are brought to engage threads on a jar neck.

Instead of forming lugs in the double wall of the skirt, screw threads may be pressed in, and may extend from the lower edge upwardly for a considerable distance. In Fig. 2, a single continuous screw thread 70 is shown, starting at 8 in the lower edge and running upward, whereby such cap can be screwed on a container provided with a similar screw thread.

In Figs. 3 and 4 I show another form of 75 cap in which the double walls have a multiple screw thread; four screw threads 9 being shown that start at four places equally spaced apart on the bottom edge, and which threads extend upwardly. This cap can 80 screw on a container having four similar threads, or can engage a container provided with four lugs adapted to enter the thread grooves on the inner wall of the cap.

In the several views described, the cap is 85 shown as provided with an overhanging rim portion 12, formed by extending the top wall 2 outwardly, then bending it back on itself, and then extending it downwardly, to form the skirt. The upper free edge of 90 the outer wall 4 is preferably brought adjacent this rim, so that it is covered and practically concealed, and can not engage the hand of the user in applying and removing the closure, and is thus protected 95 from rust.

In Fig. 5 I show a closure with the skirt about as long as the diameter of the top, which caps are generally known in the trade as catsup caps and are provided with 100 screw threads for about one-half of the skirt portion. It will be seen this cap comprises a top 13 with a downwardly extending skirt 14 that is bent outwardly and upwardly to provide an outer skirt wall 15. This could 105 be extended to the top similar to Fig. 2,

but is shown as extending upward about one-half the height of the skirt. The free or raw edge 16 is concealed by forming a bead 17 in the skirt that overhangs this raw edge thus likewise forming a protecting rim. This double skirt wall is provided with screw threads 3 for the extent of its height. In Fig. 6 a similar construction of catsup cap is shown, with the raw edge 18 pressed inwardly into a groove 19 in the skirt to conceal the raw edge. It will be seen that the screw thread extends upwardly from the bottom edge and is composed entirely of doubled contacting walls.

In Figs. 7 and 8 I show another form in which the top 20 has a skirt 21 that is bent upwardly to form a wall 22, and this latter wall has the upper edge bent over inwardly to form a bead 23. This double wall skirt formed by portions 21, and 22 is provided with lugs or screw threads 24 such as shown in Figs. 1 and 2, but the outer wall does not extend upward to the top of the cap, but has its raw edge protected by the bead formed thereon.

In Fig. 9, I show another form of cap comprising a top wall 30 having a skirt 31 bent over inwardly and extending upwardly in engagement with the outer wall, and the free or raw edge is at the upper portion near the top, where it would be engaged by the liner. This double skirt wall is impressed to form screw threads 35 which screw threads extend to the bottom of the cap.

In Figs. 10, 11, and 12, I show one process of forming this kind of closure when the flange is not too deep. The flat blank 25 may be pressed into a hat shaped form, as shown in Fig. 11, with the skirt 26 having a portion 27 projecting outwardly, and a rim portion 28 at the top. The portion 27 is bent upwardly against the skirt wall 26; and the rim 28 is pressed outwardly as indicated in Fig. 12. When making a cap having a deep flange, such as a catsup cap, this style of cap may be made in any of the well-known ways, the flange of course being cut of sufficient depth to provide for the upturned portion.

Since the skirt is formed of two walls instead of one wall, it can be constructed of lighter material, that is, of thinner sheet metal; and the doubled rim portion 12 also serves to reinforce the cap at this place. This structure will eliminate the employment of any beaded raw edge, as the raw edge of the skirt is located at the upper part of the outer wall and beneath the overhanging rim; or beneath the bead on the skirt.

What I claim is:—

1. A sheet metal closure for containers, comprising a top and a skirt portion that is extended downwardly and then extended upward for a considerable distance in engagement with the face of said skirt portion, a plurality of double-walled helical grooves

formed in the skirt by depression of both of said contacting walls of the skirt, and means for protecting the raw edge of said upwardly extending skirt portion.

2. A sheet metal closure for containers, comprising a top and a downwardly extending skirt portion, the top being doubled back inwardly on itself to form a rim projecting outwardly beyond the skirt, the skirt portion being extended downwardly and then extended upwardly in engagement with the face of said skirt with the edge of the upwardly extending wall located beneath and adjacent said top rim portion and a plurality of double-walled lugs formed in the skirt by depression of both of said engaging walls of the skirt.

3. A sheet metal closure for containers, comprising a top and a downwardly extending skirt portion, the top being doubled back inwardly on itself to form a rim projecting outwardly beyond the skirt, the skirt portion being extended downwardly and then extended upwardly in engagement with the outer face of the said skirt portion with the edge of the upwardly extending wall located beneath and adjacent said top rim portion, and a plurality of double-walled lugs formed in the skirt by depression of both of said engaging walls of the skirt and which lugs are helically inclined to screw on a suitably arranged container top portion.

4. A sheet metal closure for containers, comprising a top and a downwardly extending skirt portion, the top being doubled back inwardly on itself to form a rim projecting outwardly beyond the skirt portion, the skirt portion, being extended downwardly and then extended upwardly in engagement with the outer face of the said skirt portion with the edge of the upwardly extending wall located beneath and adjacent said top rim portion, and double-walled helical grooves formed in the skirt by depression of both of said walls of the skirt arranged to screw on a container top.

5. A sheet metal closure for containers, comprising top and a downwardly extending skirt portion, the top being doubled back inwardly on itself to form a rim projecting outwardly beyond the skirt portion, the skirt portion being extended downwardly and then extended upwardly in engagement with the outer face of the said skirt portion with the edge of the upwardly extending wall located beneath and adjacent said top rim portion, and double-walled helical grooves formed in the skirt by depression of both of said walls of the skirt, which grooves extend down to the bottom wall of the skirt.

6. A metal cap having a depending flange or skirt having a depth substantially equal to the diameter of the cap and bent upwardly at its lower edge for a considerable

distance of the flange thereby to strengthen the flange and form a closely engaging double wall, said flange having means formed from the metal at such double wall 5 for holding the cap on to a container.

7. A metal cap having a depending flange or skirt having a depth substantially equal to the diameter of the cap and bent upwardly at its lower edge for a considerable 10 distance of the flange thereby to strengthen the flange and form a closely engaging double wall, said flange having an inwardly extending locking projection formed from the metal at said double wall.

15 8. A metal cap having a depending flange or skirt having a depth substantially equal to the diameter of the cap and bent upwardly at its lower edge for a considerable distance of the flange thereby to strengthen the flange and form a closely engaging double wall, said flange having threads formed from the metal at said double wall.

9. A metal cap having a depending flange or skirt having a depth substantially equal 25 to the diameter of the cap and bent upwardly at its lower edge for a considerable distance of the flange thereby to strengthen the flange and form a closely engaging double wall, said flange having a continuous 30 thread formed from the metal at said double wall.

10. A metal cap having a depending flange or skirt having a depth substantially equal to the diameter of the cap and bent 35 upwardly at its lower edge for a considerable distance of the flange thereby to strengthen the flange and form a closely engaging double wall, said flange having means formed from the metal at such double 40 wall for holding the cap on to a container, and said cap having means for protecting

the raw edge of said upwardly extending portion.

11. A metal cap having a depending flange or skirt having a depth substantially 45 equal to the diameter of the cap and bent upwardly at its lower edge for a considerable distance of the flange thereby to strengthen the flange and form a closely engaging double wall, said flange having a 50 thread-like projection formed from the metal at said double wall, and said cap also having means for protecting the raw edge of said upwardly extending portion.

12. A metal cap having a depending flange or skirt bent upwardly at its lower edge for a considerable distance of the flange, thereby to strengthen the flange and form a closely engaging double wall, said flange having a continuous thread formed 60 from the metal of said double wall.

13. A metal cap having a depending flange or skirt bent upwardly at its lower edge for a considerable distance of the flange, thereby to strengthen the flange and 65 form a closely engaging double wall, said flange having a continuous thread formed from the metal of said double wall, and said cap having means for protecting the raw edge of said upwardly extending portion. 70

14. A sheet metal closure for containers comprising a top and a downwardly extending flange having an outwardly projecting rim, the flange being bent at its lower edge to extend upwardly in engagement with the 75 face of the flange thereby to form a double wall with the free edge of the upwardly extending portion located adjacent to said rim, said double wall having a double walled locking projection formed from said 80 flange.

WILLIAM H. REID.
